FLUID PUMP

Heinrich List, Berlin-Lichterfelde, Germany

Application July 1, 1938, Serial No. 216,949
In Germany July 6, 1937

14 Claims. (Cl. 103—53)

This invention relates to a conveying device for fluid media, adapted to operate, for example, as a fluid pump, and has for a general object to provide a conveying device of simple structure and operation which may be operated with the expenditure of very little power.

A further object of the invention is to provide an electromagnetically driven pump which is inexpensive to produce and though small may deliver an appreciable amount of air suitable for a great variety of purposes. These and other objects will be apparent from the following description and the appendant claims.

In the accompanying drawings several embodiments of the invention are illustrated by way of example only and are not intended to restrict the invention which is defined by the appended claims.

In the drawings:

Figs. 1 to 4 show various embodiments and details.

Figs. 5 to 10 illustrate diagrammatically various examples of the construction of the magnet frame, the armature and the winding.

Figs. 11 to 14 show various devices, wherein an oscillating element acting as diaphragm or piston is connected to the armature of a vibrating motor and is operated thereby.

In general the pump of the present invention comprises a working chamber having side walls 11, 12 and a pair of end walls of which one is formed by an oscillatable element such as 10 and the other by a fixed element such as 3. At least one of the end walls, for example the fixed wall as in Figures 1 to 5 or the movable wall as in Figures 6, 7, 9, and 10 to 12 or both walls as in Figures 7 and 13, is curved. The end walls formed by the members such as 3 and 10 are convergent so as to define at least one edge of the working chamber and the oscillatable member is so constrained in its movement towards the opposite wall that the line of contact advances progressively along said walls. The movement, in effect, is equivalent to a rolling movement between the two walls and, in some cases, may actually be a rolling movement.

It follows that in order to attain this effect it is necessary for the oscillatable member to be free to move longitudinally relatively to the opposite wall, at least at the part remote from the edge defined at the point of convergence. Thus, in Figure 1 the free end of the member 10 moves through a curved path and therefore longitudinally of the member 1, 2, 3.

Referring now more specifically to the various figures of the drawings:

In Figure 1 a magnet frame consisting of laminating plates is indicated at 1, whilst 2 and 3 are the operating poles of a magnet, formed to present a curved surface and 4 is an intermediate piece of non-magnetic material conforming to said curve. Secured to the operating pole 2 there is a member 5, the free end of which is capable of oscillating between narrow limits, said member acting as an extension of the operating pole. A resilient armature 10 is fastened to this member by means of rivets or screws 9. The magnet limbs 2 and 3 carry windings 7 and 8. 11 is a casing, the front wall of which is indicated at 12 and conforms to the path of movement of the end of the armature 10. Secured to the wall 12 there is a springy plate 13, which covers the valve opening 14 in the wall 12 and is itself provided with apertures, staggered with reference to the valve opening 14 and not shown in the drawings. 15 is a discharge nozzle. The device is conveniently operated by means of alternating current and its operation is as follows:

When the current flows through in one direction the operating pole 3 forms, for example, the negative pole, the pole 2 being then the positive pole, the positive pole being continued in the extension 5 right into the armature 10. The freely oscillating end of the armature 10 is in a position of readiness slightly spaced above the upper edge of the side wall of the casing, so that an inlet opening 16 is formed at this point. Owing to the opposite polarity obtaining between the freely oscillating end of the armature 10 and the operating pole 3 the armature 10 is attracted by the pole 3, first weakly and then with gradually increasing strength. The line of contact between the walls of the working chamber thus advances progressively towards the discharge nozzle 15, giving the effect of a rolling motion, so that the air contained in the operating chamber at 11 is compressed until the valve plate 13 is lifted and the compressed air is discharged through the openings 14 and the nozzle 15 under a pressure of desired value. As the current passes through the centre of amplitude the magnet becomes non-magnetic for a short period, so that the tensioned armature springs back into the position shown in the drawings and releases the opening 16 and is then again attracted when the direction of the current changes, that is to say, in the case of the usual 50 cycle mains alternating current the

armature performs 100 working strokes per second and owing to this high frequency conveys or compresses a large quantity of air even if the strokes are small. The extension 5 of the operating pole 2 conveniently consists of a resilient, magnetizable material, so that by the oscillation of the free end the result may be obtained that even if the whole device is of small measurements the armature 10 springs back far, thereby forming a large operating chamber without the necessity of the armature having to bend too much at each working stroke. This considerably lengthens the useful life of the device and ensures trouble free operation, so that even with a small device according to the invention, inexpensive to produce, a sufficient amount of air can be supplied for a great variety of purposes. In Fig. 1 the movement of the oscillating armature is exaggerated for clearness.

The heating which must be put up with in electromagnets is not lost in the invention as energy, but is utilized for increasing efficiency, because all heat discharged into the gaseous medium to be conveyed during and after the compression additionally increases the discharge velocity of the medium owing to the increase of the energy content thereof. In the present case this heat is given off mainly by the resilient armature, which becomes heated owing to the frequent reversal of magnetization. Obviously, the whole device may be disposed in a casing of any desired shape, not shown in the drawings for clearness.

Fig. 2 diagrammatically represents a nozzle arrangement, operating according to the known jet effect. In this example the tapered nozzle 15 is disposed directly on the wall 12 of the casing. In front of the nozzle 15, spaced therefrom, there is a tapered catch nozzle 17, which has a tubular extension 18. In this arrangement the jet of air issuing from the nozzle 15 drags additional air with it from the atmosphere with the aid of the nozzle 17, and if the tube 18 is of sufficient length congestion occurs when the armature springs back, and this prevents the air from returning from the tube 18 into the operating chamber 11 through the nozzle 15. In this manner it is possible to cause the arrangement according to the invention to operate without valves, and thereby to reduce wear to a minimum even in the case of continuous operation.

Fig. 3 shows an embodiment of the invention employing a rigid rolling armature 10 and having two working chambers. In this arrangement the magnet frame preferably comprises two magnets 2 and 3, which are alternately energized with the aid of direct or alternating current and are suitably insulated from one another magnetically by means of an intermediate piece 4. This embodiment is suitable for use more especially in cases where a current of air without high pressure is necessary, for example for use as a fan. The armature 10 consists of a flat non-flexible plate of magnetizable material. At its ends blade springs 19 and 20 of the same width as the armature are mounted. The armature oscillates between two lateral walls 21, wherein the valve openings 22 and 23 are provided within the areas bounded by the blade springs 19 and 20. A compression spring 25 is supported on a bridge 24 connecting the casing walls, said spring pressing on the armature at the centre of oscillation thereof, thereby ensuring that the operating chambers are sealed with reference to one another. Conveniently, the curved rolling path on the magnet

frame and the underside of the armature, as well as the side edges thereof are ground, thus to obtain adequate seal between the operating chambers and between these and the atmosphere.

Fig. 4 shows a construction similar to Fig. 1, but with the difference that in this case the winding 8 is disposed in a transversely laminated magnet frame 1. The winding may be covered by non-magnetic intermediate layers 26.

Fig. 5 shows diagrammatically an arrangement also similar to Fig. 1, but having only one magnet limb surrounded by a winding. In this and in the following figures the casing parts are omitted for clearness.

Fig. 6 illustrates an embodiment, wherein the surface of the laminated magnet frame 1 has an infinite radius of curvature, i. e. is formed with a plane surface. The resilient armature 10 is curved and is attracted by the surface of the magnet frame at each operative stroke.

In the embodiment shown in Fig. 7 a curved armature 10 is provided and the surface of the magnet casing 1 is also curved. The armature is secured at the centre of the magnet casing 1, so that two operating chambers result.

In the embodiment shown in Fig. 8 the magnet casing 1 carries at its ends rollers 27 and 28 rotatable in bearings and supporting the resilient armature 10. The pole surface of the magnet casing is concave, so that the operating chamber is formed between the pole surface and the armature. The armature is attracted by the pole surface at every operative stroke and during this movement its ends roll on the rollers 27 and 28.

At suitable points compression or blade springs or rubber blocks, not shown in the drawings, are provided, which prevent the armature from being shifted from its location.

The mounting and fixing of a rigid rolling element may be conveniently effected as shown in Fig. 9. In this example at certain distances apart guide strips or wires 29 and 30 are disposed on the magnet frame, which comprises the alternately energized magnets 2 and 3 and the non-magnetic intermediate piece 4, the said strips or wires being alternately secured at one of their ends to the magnet frame and their other ends to the rolling armature 10. This arrangement, which is known in connection with rolling elements of other types, has the advantage that it provides a good guide for the rolling armature even in continuous operation.

Evidently, for example the mid-portion of the rolling element may also consist of non-magnetic material, so that only the ends act as the armatures of the alternately energized magnet. Hereinafter this drive is referred to as "remote drive."

For avoiding undesirable vibration the weight of the armature is as small as possible with reference to that of the frame. Fig. 10 shows that two or more armatures may be disposed on one magnet frame. If, for this purpose, for example the magnet frame shown in Fig. 6 is employed, two operating chambers are formed as shown in Fig. 10, and by their simultaneous response the armatures compensate for the oscillations occurring in the system.

The "remote drive" already referred to is also employed in the embodiments shown in Figs. 11 to 14. Fig. 11 shows diagrammatically a magnet frame 1, the operating poles 2 of which attract the armature 10 mounted on the resilient oscillating element 31 according to the frequency

of the current impulses. The armature 10 is returned and guided by the element 31.

In the embodiment shown in Fig. 12 two blade springs 31 are secured to a rigid intermediate element 32 and are interconnected by a wall 33 which vibrates therewith. To this wall is secured with the aid of the holder element 34 the armature 10, which is attracted by the operating poles 36 provided on the laminated magnet frame 35 and is returned into the position of readiness by a return spring, not shown.

The embodiment shown in Fig. 13 comprises a circular or curve shaped casing part 1, which has projecting walls 2 on both sides, a resilient oscillating element 3 secured to the casing 1 being disposed between these walls. The free end of this spring strip is pulled tight on to the outer periphery of the casing 1 by the armature 10 of the vibrating motor 35 through the lever 34 and is returned into the position of readiness by a return spring 43 mounted in a suitable position. Conveniently, a roller 44 is provided between the free end of the spring strip 3 and the casing 1, said roller firstly acting as sealing means and secondly eliminating friction between the end of the spring strip and the wall of the casing.

Fig. 14 shows the device in section on the chain dotted line of Fig. 13. The operation is as follows: In the position shown the strip spring 3 projects over the upper edge of the lateral walls 2 to such an extent that between the strip spring and the upper edge an inlet opening is formed. If now the armature 10 of the magnet is attracted by the operating poles 36, the strip spring is actuated by the lever 34 and compresses the air between the casing 1 and the spring 3, until the tension of the valve plate 45 disposed over a discharge opening is overcome and said plate is lifted off the wall 1. In this manner the compressed air passes into the storage chamber 46 formed by the casing 1, which is provided with a regulable outlet valve 41.

The air blower according to the invention may also be employed for the operation of a dust extractor. The suction nozzle or a rigid suction mouthpiece and the dust catching means may be connected either to the inlet opening 16 (Fig. 1), to the catch funnel 17 (Fig. 2) or to both. For this utilization particularly the valveless embodiment already described is suitable.

From the foregoing description it will be appreciated that in one embodiment of the invention there is provided an oscillating armature which is resilient and oscillates in an operating chamber formed by the armature, the magnet frame and suitably formed casing element, the magnetic arrangement forming the compression means. The invention is not limited to the use of alternating current since the oscillating system could operate self-interrupting contacts so that direct current could be employed. The device of the present invention may have inlet and outlet valves disposed on the armature on the casing or may operate without valves, for example with the jet effect as hereinbefore described. If valves are used preferably these are disposed on the casing to avoid an increase in the weight of the armature.

It will be readily appreciated that the invention is not restricted to the examples shown or to the shapes thereof and that further constructional modification may be made without leaving the scope of the invention.

I claim:

1. A conveying device for fluid media, having a plurality of walls forming a working chamber, one of said walls being constituted by a power operated oscillatable member which converges into contact with an opposite wall to define at least one edge of the chamber and which is free to move longitudinally relatively to said wall at least at the part remote from said edge, at least one of said converging walls being curved, and means being provided whereby the wall formed by the oscillatable member is so constrained in its movement towards the opposite wall that the line of contact advances progressively along said walls.

15 2. A conveying device for fluid media, comprising a compression chamber having a fixed wall and opposite thereto a movable wall formed by a flexible plate secured only at a part of its edge to, and having the other parts of its edge free from said fixed wall and set to form an acute angle therewith, and an electromagnetic motor for flexing said plate towards and away from said fixed wall, at least one of said walls being so curved that during said flexing the line of contact between the walls advances progressively along them.

20 3. A conveying device for fluid media, comprising a casing forming a working chamber, said chamber having a fixed wall provided with a resilient flexible extension at one end, and opposite thereto a movable wall formed by a flexible plate secured at one end to said extension and set to form an acute angle therewith, said plate forming the armature of an electromagnetic motor by which it is flexed towards and away from said fixed wall, and at least one of said walls being so curved that during said flexing the line of contact advances progressively along said walls.

25 4. A conveying device for fluid media comprising a casing forming a working chamber, said chamber having a fixed wall formed at least partly by the pole face of an electromagnet, a movable wall opposite thereto which is free at one end and converges at its other end into contact with the fixed wall, and forms the armature of said electromagnet, and side walls between which said armature moves, said armature having a resilient connection with said fixed wall which, when the magnet is inoperative maintains the free end, of the armature projecting beyond the side walls of the casing to form an inlet, whilst the magnet in operating is adapted to force said free end into the casing, closing said inlet, at least one of said walls being so curved that during said inward movement of the armature the line of contact between it and the fixed wall advances progressively.

30 5. A conveying device for fluid media, comprising a casing forming a working chamber, said chamber having a concave fixed wall formed at least partly by the pole face of an electromagnet, and opposite thereto a movable wall formed by a resilient armature member adapted to be vibrated by the magnet, said armature being supported on roller elements at the edges of said fixed wall so as to form with the latter a working chamber, opposite sides of which converge into contact and so that during inward movement of the armature said line of contact will advance progressively.

35 6. A conveying device for fluid media having a plurality of walls forming a working chamber, one of said walls being fixed and formed at least partly by the pole face of an electromagnet

and the wall opposite thereto being formed by a curved armature member rockably supported on said pole face, said magnet in operation being adapted to rock said armature whereby the line of contact between it and said fixed wall will move to and fro.

7. A conveying device for fluid media, comprising a plurality of walls forming a working chamber, two of said walls opposite to one another converging into contact to define at least one edge of the chamber, at least one of said walls being free to move longitudinally relatively to the other wall at least at the part remote from said edge, means for producing relative movement of said walls towards and away from one another, and means whereby the line of contact between said walls is caused to move progressively to and fro simultaneously with the relative movement of the walls.

8. A pump for fluid, comprising a compression chamber having side walls, a pair of oppositely disposed end walls, at least one of which is curved, arranged to converge towards one another, the end and side walls together giving the chamber a wedge like form, said end walls being mounted for movement with respect to one another along at least their major part and between said side walls, means being provided to constrain said end walls to make contact along a line which moves to and fro during such movement, inlet and outlet for said fluid and power means operatively connected to one end wall for alternately moving said wall towards and away from the other.

9. A device for propelling fluid comprising a hollow wedge-like structure having fixed side walls and a pair of relatively movable end walls disposed to converge at an acute angle, one at least of said end walls being curved, inlet and outlet for said fluid in said structure, and power means operatively connected to one end wall for alternately moving said wall towards and away from the other end wall so that the line of contact between said walls advances progressively.

10. A device for propelling fluid, comprising a hollow wedge like structure having fixed side walls, a fixed end wall having a convex surface, a second end wall disposed to converge at an

acute angle with said fixed end wall and mounted for movement along a greater part thereof towards and away from the fixed wall so that the line of contact therebetween advances progressively, inlet and outlet for said fluid in said structure and electromagnetic means forming an integral part of said fixed end wall and arranged to attract periodically said movable end wall towards itself.

11. A device for propelling fluid, comprising a hollow wedge-like structure having fixed side walls and a pair of relatively movable end walls disposed to converge at an acute angle, both of said end walls being curved in directions away from each other, inlet and outlet for said fluid in said structure, and electromagnetic power means forming an integral part of one of said end walls for operatively influencing the other of said end walls and for alternately moving said other end wall towards and away from said means.

12. A device for propelling fluid comprising a hollow wedge-like structure having fixed side walls, a fixed end wall, a second end wall connected at one end to said fixed end wall and curved away from said fixed wall towards a free end of said second end wall, inlet and outlet for said fluid in said structure, and power means operatively connected to the second end wall for alternately moving said free end of said second wall towards and away from the said fixed end wall so that the line of contact between said end walls advances progressively.

13. A device as claimed in claim 12 in which the said power means comprises an electromagnetic forming an integral part of said fixed wall.

14. A device for propelling fluid comprising a hollow wedge-like structure having fixed side walls, a rigid convex end wall, a flexible convex end wall in contact at one part with said rigid wall, inlet and outlet for said fluid in said structure, and power means operatively associated with said flexible wall for periodically moving said wall into contact with said rigid end wall at parts other than said one part so that the line of contact between said walls advances progressively.

HEINRICH LIST.
